UNITED STATES PATENT OFFICE.

FRITZ LOWENSTEIN, OF NEW YORK, N. Y.; JOHN C. WAIT, ADMINISTRATOR OF SAID
FRITZ LOWENSTEIN, DECEASED, ASSIGNOR, BY MESNE ASSIGNMENTS, TO RADIO
CORPORATION OF AMERICA, A CORPORATION OF DELAWARE.

WIRELESS TELEGRAPH APPARATUS.

Application filed June 28, 1910. Serial No. 569,324.

My invention relates to improvements in wireless telegraphy.

The objects of my invention are to provide a simple, readily operated apparatus which will enable the operator to quickly adjust and tune his apparatus both in receiving and transmitting. With this general object in view my invention consists in the features, details of construction and combination of parts which are first described in connection with the accompanying drawings and then more particularly pointed out in the claims.

Referring to the drawings:

Fig. 1 is a diagram of transmitter circuits employed by me;

Fig. 2 is a detailed elevation of the mechanical parts for operating the transmitter;

Figs. 3, 4, 4^a and 5 are diagrammatic views of different forms of receiving circuits embodying my invention;

Fig. 6 is a plan view of the receiver shown diagrammatically in Fig. 4;

Figs. 7 and 8 are diagrams illustrating the principles involved in my receiving elements;

Fig. 9 is a diagram illustrating the characteristics of some elements of the apparatus employed in Fig. 5;

Fig. 10 is a plan view and Fig. 11 a vertical section of the variable self inductance and capacity employed by me;

Fig. 12 is a diagram illustrating the method of determining the constants of an antenna;

Fig. 13 is a diagram showing the gearing.

Referring to the drawings, and more particularly to Fig. 1, which illustrates diagrammatically a practical form of the transmitter circuits, 100 represents a line switch connecting direct current supply mains 101 with circuit 102 of a direct current motor 103 having series and shunt field windings 104 and 105, respectively. Said motor is arranged to drive alternating current generator 106 whose series and shunt field windings are indicated at 107 and 108, respectively. A regulator for the generator field is indicated at 108^a; and a generator-compounding adjuster at 108^b. Protecting devices 109, 110, 111 and 112 are provided for protecting against high frequency high potential break down of the direct current motor, alternating current generator, and

the shunt field windings and series field 55 windings of the generator, respectively. These protecting devices may be of any usual or suitable form and require no detailed description.

The alternating current generator supplies 60 power to the primary 113 of a resonance transformer of which the secondary is indicated at 114, this secondary feeding the closed or oscillating circuit of the transmitter system. The secondary may have its 65 end turns air insulated as indicated at 114^a. A protecting device for the transformer is provided as shown at 115. The oscillating circuit includes condenser 116, spark gap 117, which is here shown as of the quenched 70 type, primary inductance or helix 118, and loose coupling coil 129.

The spark gap may be cooled as by fan 119, whose circuit is provided with protecting device 120.

By means of lightning switch 121, the antenna 122 may be connected either to ground, or to conductor 123 which, in turn, may be connected by arm 124 of an antenna switch device, which will be described later 80 in detail, either to the receiver circuit through lead 125, or to ground through lead 126, variable inductance 127, movable contact 9, secondary inductance 128, double movable bridging contact 12, 13, primary inductance 118, coupling coil 129, and movable contact 8. A hot wire ammeter 130 may be inserted in the ground connection, as shown. The variable loose coupling coil 129 between the primary inductance 118 and the secondary 90 inductance 128 is adjustable about its axis 131 that the coil may be moved to bring its axis either in line with the axes of coils 118 and 128 or at right angles to said axes; or the coupling coil may be made to assume 95 any intermediate position between these extremes.

The loose coupling shaft is diagrammatically indicated in Fig. 1, while in Fig. 2 are shown means for turning the shaft, which 100 means will be more fully hereinafter described. The mutual induction or coupling between the primary and secondary helices may therefore be varied as desired.

The primary and secondary helices are 105 tapped off at certain points and, as indicated in Fig. 1, are connected in groups to corresponding contact points I, II, III, IV, and

V, and 1, 2, 3, 4 and 5. These taps are arranged so that the primary and secondary circuits as shown diagrammatically in Fig. 1 remain in syntony for any position of the transmitter lever 6, or for any position of the transmitter wheel 7, Fig. 2. The two contact brushes 8 and 9 which are operated by the wheel 7 are turned jointly by provision of bevel gears 10 and 11 and insulator shaft 7^a. The contact brush 12 of the primary helix and 13 of the secondary helix are one piece mechanically placed in opposite directions on one arm and therefore move jointly by the operation of the lever 6. 15 As shown in Fig. 1 the operation of the lever 6 will change the self-inductance of the primary and secondary circuits in large steps thereby enabling the operator to send out in quick succession five different wave lengths over a comparatively large range. 20 On the other hand the subdivisions of self-inductance leading to the contact points I, II, III, IV and V are comparatively small and adjusted so as to give five wave lengths 25 between any two wave lengths given by the lever.

The wheel 7 may be left at any one position and lever 6 operated over five wave lengths or lever 6 may be left at any one 30 position and the wheel turned over its contact points whereby another set of five wave lengths are obtained in ready succession which five wave lengths have smaller steps between themselves than the wave lengths 35 obtained by operation of the lever 6.

An intermittent gear 14—15 is provided by means of which after each complete revolution of the wheel the lever is advanced to the next contact point. I am thus enabled 40 to obtain 25 different wave lengths by the transmitter arrangement as shown in Fig. 2 by a continuous turning of the wheel 7 for five complete revolutions.

The object of this design is to adjust the 45 transmitter rapidly to any wave lengths desired without recourse to several operations or diagrams and to provide means for interference.

In Fig. 1 the sending key is shown, which 50 combines the feature of a minimum of arcing with safety from danger due to high voltage currents on the other apparatus when the key is open. In this view 16 represents a self-inductance with two windings 55 which are connected in such way that when they are traversed by the primary current their magnetomotive forces are opposite and equal so as not to produce magnetic field in the iron core. When sending key 17 is depressed during transmitting this device 16 does not offer any more resistance to the 60 passage of the current than that given by the ohmic resistances of the windings. Key 17 has two current breaks 18 and 19. In releasing the key, contact 18 will break first

and as the current which flows through this contact can be made to be a small part only of the total current of the primary circuit, the arcing at this point 18 is greatly reduced. After contact at point 18 has broken the primary current can only run through the upper half of the iron core winding and exerting its magnetomotive force will produce a considerable counterelectromotive force thereby reducing the total primary current 75 to a small fraction of its original value, so that at the moment when contact 19 breaks the current is so small that there is no appreciable arcing at this break. For quick and reliable operation of the transmitter 80 non-arching keys are very important and this therefore constitutes an important feature of my invention.

The novel antenna switch device above referred to is useful particularly in connection with what is known as break key operation, whereby the operator is enabled to "listen in" for incoming signals during the brief intervals occurring between the dots and dashes of his own signals. In the present instance, this antenna switch device has a shaft 132 of suitable insulating material such as micanite or the like, to which are secured the metal contacter 124 above mentioned, and another metal contacter 133 85 which is adapted to close the gap 134 between leads 135 and 136 when the switch is in a position to permit this. The leads 135, 136, connect the alternating current generator with the resonance transformer when key 17 is depressed into sending position and gap 134 is closed. The transmitter key 17 has an insulated bridging contact 17^a attached to the rear part of its lever, and when the key is in rest position, this contact closes 90 the open gap 137 in circuit 138, 139 which includes the magnet 140 whose iron armature 141 is mounted on the switch shaft 132. A tension spring 142 is arranged to draw the magnet armature away from the magnet 140 when the circuit of the latter is open, thereby moving the switch device to close the gap 134 and connect the antenna to lead 126, thus putting the system in condition for 100 sending. In the position shown in Fig. 1, however, the transmitter key is in rest position, the magnet is energized, and it therefore attracts armature 141 against the action of the tension spring. Consequently the circuit 135, 136 is opened, and no power is supplied to the transformer. By means of this arrangement, when the antenna switch is set for receiving, the current from the antenna does not pass through the transmitter inductance, but only through the receiver circuit. In this way the setting of the receiver for any particular wave length is independent of the setting of the transmitter. 115 In the present arrangement, provision is also made for preventing arcing over the 120 125 130

contact points 1, 2, 3, 4, and 5 while varying wave lengths through manipulation of the transmitter handle 6. As shown in Fig. 1, the transmitter handle is here provided with an arm 143 carrying an insulated metallic bridge 144 which is adapted to be moved to close any one of the parallel gaps 145 in which the leads 146 and 147 terminate. These leads are also connected to the magnet circuit 138 and 139, and when any one of the gaps 145 is closed, the magnet circuit is also closed to energize the magnet 140 and thereby to open the power circuit supplying the transformer. The arrangement of parts is such that the bridge 144 closes the magnet circuit just before the movable connector 12, 13 breaks connection between the transmitter helices in passing from one pair of contact points 1, 2, 3, 4 and 5 to the next pair. As soon as connection between the next pair of contact points is established, the bridge 144 opens the magnet circuit, whereby the power circuit to the transformer is again closed. Having now explained the application of certain principles of the invention to a transmitter system, I will proceed to describe a practical arrangement of the receiver. The principal object of my invention, as concerns the receiver, is to adjust the primary and secondary circuits thereof in such way that they may automatically remain in tune over a wide range of wave lengths. It has heretofore been considered impossible to achieve this result because of the generally adopted views of many experimenters and investigators that the behaviour of an antenna is not similar to that of a self-inductance or a capacity. The complex nature of the reactance curves which have been plotted for many antennæ has made it appear that an antenna could not be represented in its electrical functions by simple electrical instrument values or elements like capacity and self-inductance. On the contrary, I have found that an antenna may in fact be represented by a lumped capacity and self-inductance.

Fig. 12 shows a diagram drawing for the purpose of determining self-inductances and a capacity value which may be substituted electrically for an antenna. It has heretofore been known that the antenna has a variable reactance for different wave lengths but heretofore no law was established of the nature of the change. I have discovered that if the reactance curve of an antenna be plotted in reference to w , (which represents $2\pi f$) as abscissæ, a parabola will result. Assuming that a number of reactances at an equal number of frequencies have been measured, then by selecting any two points the parabola may be plotted and from it may be derived the absolute value of the antenna capacity and the absolute

value of the antenna self-inductance, which absolute values remain constant for all wave lengths from the natural wave length up.

If, for example, a number of values, $\frac{1}{c}$, of reactances at different frequencies, say five, have been obtained by actual measurement of an antenna, these may be plotted as ordinates, with the corresponding wave lengths as abscissæ, thus giving a graph which is a parabola, as illustrated in Fig. 12. If now any two points in this parabola be selected and the corresponding ordinates and abscissæ measured and their values determined from the scale of the drawing, the constant value C_a of the antenna capacity and the similar value L_a of its self inductance may be calculated from the formula:

$$\frac{1}{c_a} = \frac{1}{c_1} + w_1^2 L_a \quad 85$$

$$\frac{1}{c_a} = \frac{1}{c_2} + w_2^2 L_a$$

which formula is obviously deducible from the equation of the parabola and the electrical formula of reactance.

The above formula may be deduced as follows: When a given voltage is applied to a circuit containing capacity and self-inductance the amount of alternating current is governed by the impedance of the circuit. The frequency may be designated by the letter f . The quantity $2\pi f$ is commonly designated by the letter w . The reactance of a capacity C is $\frac{1}{wC}$. The reactance of a self-inductance L is wL . A circuit containing both capacity and self-inductance has a reactance

$$\frac{1}{wC} - wL.$$

If an antenna be made a part of an oscillatory circuit to which a frequency f_1 , arbitrarily chosen, be imparted, the antenna may be substituted with impunity by a capacity the reactance of which, $\frac{1}{w_1 C_1}$, is equal to the antenna reactance, 115

$$\frac{1}{w_1 C_1} - w_1 L_a;$$

where C_a and L_a are fixed values of capacity and self-inductance, respectively, representing the antenna. Therefore

$$\frac{1}{w_1 C_1} = \frac{1}{w_1 C_a} - w_1 L_a.$$

This substitution capacity C_1 is found by the usual resonance method, viz: With the antenna included in an oscillatory circuit a frequency f_1 is applied

$$(2\pi f_1 = w_1)$$

and the circuit tuned to resonance; then the antenna is disconnected and in its place a condenser is inserted which is then adjusted so as to again obtain resonance. The capacity value C_1 of this condenser then indicates the reactance value of the antenna:

$$\frac{1}{w_1 C_1} = \frac{1}{w_1 C_a} - w_1 L_a$$

10 or

$$\frac{1}{C_a} = \frac{1}{C_1} + w_1^2 L_a,$$

which formula was to be deduced. A second frequency

$$f_2(2\pi f_2 = w_2)$$

furnishes a similar equation

$$20 \quad \frac{1}{C_a} = \frac{1}{C_2} + w_2^2 L_a.$$

In these two equations, w_1 and w_2 are given (arbitrarily chosen); and C_1 and C_2 are determined by substitution measurement as above explained; leaving the two unknown quantities C_a and L_a which are found in the usual elementary way of solving two equations for two unknowns.

Plotting the values

$$30 \quad \frac{1}{C_1}, \frac{1}{C_2}, \dots, \frac{1}{C_n}$$

against their corresponding values of $w_1, w_2, \dots, w_n$ as abscissæ, a parabola is found as the locus of the $\frac{1}{C}$ values as clearly indicated by the parabolic nature of the above equation written in a general form

$$40 \quad A = x - y^2 B$$

where A stands for the constant $\frac{1}{C_a}$, B for

45 the constant L_a , x for the variable $\frac{1}{C}$, y for the variable w .

The values thus found are to be made elements for artificial antenna to be used in the local circuit.

50 Thereby I am enabled to imitate the seemingly variable antenna by two constant values of a condenser and a self-inductance. Fig. 3 shows such an artificial antenna in L''_s and C''_s . This artificial antenna, that 55 is to say, the lumped self-inductance and capacity equivalent to that of the actual antenna, is provided in the local circuit to make this circuit in effect identical with the actual antenna circuit. Thereby I am enabled to move the four variable elements of the receiver L', C', L'' and C'' simultaneously by the employment of gears or other mechanical means without at any moment disturbing syntony between the two circuits.

65 The artificial antenna may be made a copy

of the antenna to which the apparatus is to be attached, all as actually shown in Fig. 3. The artificial antenna of the local circuit may be predetermined and the real antenna adjusted by a standardizing self-inductance 70 and capacity so as to make its values equal to that of the predetermined artificial antenna.

Fig. 3 shows a standardizing self-inductance L'_s which serves to convert the primary circuit to the predetermined standard value. A standardizing condenser should be provided for the same reason. It has been omitted in Fig. 3, assumption being made that the antenna itself was adjusted to the predetermined value. Such a standard- 75 80 85 90 95 ized condenser is shown in Fig. 5 at C'_s . As shown in Fig. 3, the detector coupling is variable by plugging the detector circuit around either the variable capacity alone, or the standard artificial capacity alone, or around both in series.

In Fig. 4, L'' (I, II, III, IV) designate the self-inductance of the local receiver which self-inductance is tapped off and connected to a number of contact points 22, a contact arm 23 being provided to cut in or cut out self-inductance. 24 is a variable condenser which is also operated by an angular movement. The characteristics of 95 both the self-inductance and the capacity are shown in Figs. 7 and 8 to be of logarithmic nature. In this case the self-inductance and capacity of the artificial or equivalent standard antenna in the local circuit 100 are embodied in the variable apparatus.

In Fig. 7 the angles of displacement of the self-inductance and the capacity are shown as abscissæ while the ordinates designate the electrical values of the corresponding displacement. The equation for this logarithmic characteristic is given as

$$110 \quad y = a \left(\frac{b}{a} \right)^{\frac{x}{c}}.$$

This characteristic also fulfils the condition that the product of any two ordinates is equal to the square of that ordinate which lies half way between them. If therefore the self-inductance and the capacity be placed at certain points for the purpose of receiving a signal and then the self-inductance be increased by a certain displacement and the capacity decreased by an equal displacement, the tune of the receiving circuit is thereby not changed, since the tune depends on the product of capacity multiplied by self-inductance. Though therefore no change has been made in the tune of the circuit the stiffness has been changed and it is for this purpose and for the purpose of variable detector coupling that this logarithmic characteristic has been chosen.

Fig. 8 shows diagrammatically how a 130

wave length scale and a capacity scale may be attached mechanically to the capacity element. The pointer 25 indicating capacity is stationary and may also be seen in Figs. 6 and 10. The pointer 26 for the wave length scale is mechanically attached to the self-inductance element. See also Figs. 6, 10 and 11. Both scales are of logarithmic sub-division. Both scales are indicated by 27 in Figs. 6, 7, 8, 10 and 11. The primary coil of a loose coupling is indicated by 28 in Figs. 4, 5, and 6. In Fig. 4 the loose coupling is indicated at $M' M''$. The self-inductance is sub-divided into four sections I, II, III, IV, Figs. 4 and 6. For the purpose of avoiding losses due to dead coil ends, these sections are connected by section switches S S which are operated automatically by the self-inductance arm 23. As is clearly shown in Figs. 10 and 11, the self-inductance arm 23 is arranged to be moved so as to make contact successively with the contact points 22 which are electrically connected by means of studs 22' and suitable leads with the tapping-off points of the self-inductance, this latter not being shown in Figs. 10 and 11. Each of the section switches S S is pivoted as at P and is provided with a bifurcated projecting portion Q so disposed that one or the other of its arms always lies in the circular path in which travels actuating stud 23^a which is carried by self-inductance arm 23. As the arm 23 is moved in counter-clockwise direction as indicated by the arrow in Fig. 10, the self-inductance is increased as the arm passes over the contact points 22. Furthermore the stud 23^a acts on the section switches successively to bridge the gap between section contacts P' P'', thus cutting in the sections I, II, III and IV as required. In Fig. 10 the switch at the left is shown as just being thrown to connect sections I and II. In the same manner as the arm continues to move counter-clockwise the other two section switches will be operated to bring sections III and IV into the circuit. In traveling in the reverse direction, that is, clockwise, the stud 23^a turns the section switches in the opposite direction, opening the gaps between the pairs of contacts P' P'' to cut out the sections successively. The detector circuit is connected by a double throw switch 29, Fig. 4 by which the same may be connected with the antenna circuit to tune the primary. In throwing the switch over, the detector circuit is connected to the local circuit. By suitably manipulating switches a (Figs. 3, 4, 4^a and 5), the antenna may be optionally connected to a duplicate or reserve receiver system. This arrangement is important in that it ensures uninterrupted service in case it becomes necessary or desirable to temporarily discontinue the use of one of the receivers for purposes of repair, etc. In the same figures is indicated the antenna transfer switch b whereby the antenna may be connected either to one of the receivers or to the transmitter, as at c. After tuning the local circuit by arbitrarily varying the capacity and self-inductance an audibility may be obtained which is not a maximum obtainable. For the purpose of obtaining such maximum audibility the self-inductance and capacity of the local circuit, I, II, III, IV and 24 are mechanically coupled and turned in such way that one decreases while the other one increases for the same amount of displacement. By such turning the tune of the circuit is not disturbed but the detector coupling alone varied. It is known that there is an optimum of the detector coupling to insure a maximum of audibility. Heretofore it was very tedious to change the stiffness of a circuit and then readjust it to tune and thus possibly so much time elapsed between two readings that comparisons were impossible. By the introduction of the logarithmic characteristic of self-induction and capacity I am enabled to vary quickly the stiffness and therewith the detector coupling without throwing the circuit out of tune. In general, therefore, the percentage increase of self-inductance, capacity and wave length for a given increase of displacement is constant over the whole range. The apparent sharpness of the tuning is constant and equal to the sharpness of the received wave, no matter which part of the scale is being used. The importance of thus making equal movements of a tuning element produce equal percentage changes in self-inductance, capacity and wave length, will be clear from the following considerations: If, after a receiver circuit has been tuned, a tuning element thereof, such as the capacity, be changed a certain percentage, the signals for which the circuit has been tuned will be practically obliterated. In order to effect this percentage change, a certain geometric movement of the movable part of the tuning element has to be performed. In instruments of the type heretofore known, the geometric movement or displacement is relatively small when the original setting in tune happens to be at the lower end of the instrument scale; while, on the other hand, the actual geometric movement required to get the same percentage change in the value of the tuning element is relatively great if the initial setting in tune is at the higher end of the scale. For example, in apparatus heretofore used, if a 10 per cent change in capacity were necessary to change from maximum audibility to obliteration, then in the first case, assuming the receiver circuit to be in tune at a condenser scale setting of 20°, a movement of only 2° over the condenser scale would produce this extreme change from maximum audibility to oblition.

eration; while if the receiver circuit was in tune at a condenser scale setting of 150° , a movement of 15° would be necessary to produce the same change. To the eye and to the hand, the receiver would appear to be more sensitive for exact tuning at the lower positions of the condenser than at the higher, since the signals change over their full range of strength in the one case by a movement of 2° only, and, in the other case by a movement of 15° . Such differences in the apparent sensitiveness or sharpness of tuning in the receiving apparatus of the type heretofore known are due primarily to the fact that wave lengths, and hence oscillation periods, are proportional to the square root of the product of capacity by inductance, and hence a change in either tuning element affects the tuning in a percentual degree. Consequently, while equal geometric movements of the tuning mechanism in apparatus heretofore known did not produce equal percentage changes in tuning over different localities on the instrument scale, the arrangement which I have herein disclosed obviates this difficulty as hereinbefore explained. It is evident that, in the preferred embodiment of apparatus herein disclosed, the electrical value of each tuning element is variable in accordance with an exponential function of the distance traversed by the means movable to vary such value.

A practical method of mechanically connecting the self-inductance and capacity for operation in conformity with the present invention is shown by way of example in Figs. 10 and 11. The condenser 30, Fig. 11, shows the movable plates cut off at such different angles as to produce the logarithmic characteristic. This movable part of the condenser is turned by means of a crank 31, a crank disk 32, a shaft 33 and a knob 34. Attached to the shaft 33 is an upper clutch disk 35. The self-inductance arm 23, carrying brush 23' and pointer 26, is attached to a lower clutch disk 36 which turns individually around a post 37 by means of a handle 38. Spring 35' surrounding the vertically movable shaft 33 is compressed between the upper end of post 37 and the upper clutch disk 35, thereby tending to maintain the clutch members out of mutual engagement. Handle 38 is here shown as pivoted at 38', whereby it may be turned down to press brush 23' into firm contact with any of the contact points 22. Both the condenser and the self-inductance can be varied therefore independently for the purpose of tuning. Once tuning has been established the rubber knob 34 is depressed, thereby engaging clutch 35-36, and turning of the knob will then cause an equal amount of displacement of the self-inductance and of the capacity. As shown in Fig. 10 the capacity increases with

a clock-wise movement whereas the self-inductance increases by a movement in the opposite sense. Therefore the turning of knob 34, if clutch 35-36 is engaged, will increase the capacity and decrease the self-inductance or vice versa for the same amount of displacement, thereby obtaining the end desired. To obviate the necessity of holding the knob 34 depressed during the turning of the coupled elements a compression spring 39 has been provided, Fig. 11, which will keep the clutch members in engagement. This spring is confined between the lower end of stationary post or sleeve 37 and washer 40, which rests loosely on the hub 40' of crank disk 32, which disk is secured to the vertically slideable shaft 33. The spring therefore tends to force shaft 33 down so as to bring clutch members 35 and 36 into mutual engagement and thereby to mechanically couple the inductance and capacity elements. Spring 39 is of sufficient strength to overcome the opposing spring 35' before described. In the position of the parts here shown, spring 39 is prevented from depressing the upper clutch member by means of latch members 41 mounted on leaf springs 42 secured to a sleeve 42' which press the latch members inwardly so that their shoulders 41' may engage the under side of the washer 40. By pushing down on knob 34, the sloping cam surfaces 43 of the disk hub throw the latches 41 outwardly, thereby releasing washer 40 and the spring 39 confined thereby, the clutch 35, 36 being thereafter held in engagement by said spring. When the knob is moved upward the washer is lifted until it is caught by the projection on the latches and thereby the clutch is held in its disengaged condition.

Figs. 4^a and 5 show combinations of the two improvements shown in Figs. 3 and 4. The total capacities and self-inductances of both circuits are of a logarithmic nature, but in the arrangement illustrated in Fig. 4^a, due to the natural antenna in the primary circuit and the artificial antenna, L'', and C'', in the secondary circuit, the characteristic of the variable apparatus is not truly logarithmic but of a character of such nature that in conjunction with the constants of the circuits a capacity and self-inductance will result which is of a true logarithmic nature. In the arrangement shown in Fig. 5, the values L'' and C'', controlled by the variable apparatus, include the values L''₁ and C''₁ of Fig. 4, and hence the characteristic of said variable apparatus is truly logarithmic, as in the arrangement of Fig. 4.

Fig. 9 shows the procedure to arrive at the characteristic of these variables. In Figs. 4^a and 5 the self-inductances and capacities of both circuits are interconnected by mechanical means like gears, as indicated diagrammatically in Fig. 13, provision also

105

110

115

120

125

130

being made for disengaging any one element from the chain of gears for the purpose of individual adjustment. Mechanism for effecting this may be of any suitable character as, for example, adjustable gearing adapted to engage teeth 44 on the periphery of the crank disk 32 shown in Fig. 11. It is deemed unnecessary to illustrate such gearing in detail, the general arrangement being indicated in Fig. 13 as before stated. It is apparent that the instrument shown in Fig. 11 may be duplicated in another circuit of the system, and that when the two instruments are connected by the gearing aforesaid, the capacities in the two circuits may be varied simultaneously to vary the wave length while maintaining the circuits in tune, that is to say, in resonance. By depressing knob 34 of each instrument, the inductances, as well as the capacities, of the two circuits are also mechanically coupled, in which condition it is evident that movement of one of the knobs 34, handles 38, or equivalent controlling members, will produce simultaneous movement of all the tuning elements thus coupled. This varies the stiffness in both circuits simultaneously without changing the ratio of stiffness between said circuits and without disturbing syntony. By manipulating the intermediate gearing so as to uncouple the two instruments or sets of tuning elements, either instrument can be individually adjusted to vary the stiffness of the corresponding circuit. By releasing knobs 34 further individual adjustment as to wave length can be made. The arrangement above described has, in addition to the combined advantages of the improvements shown in Figs. 3 and 4, an additional combination advantage as follows:

In actual practice, the respective degrees of stiffnesses of the primary and secondary circuits may be set to best advantage and yet be different from one another. If, under these conditions the two instruments be mechanically coupled, the turning of any one of the knobs will change both circuits in such way that they will remain in syntony and preserve constant the ratio between the stiffness of the primary circuit $(\frac{L_1}{C_1})$ and the stiffness of the secondary circuit $(\frac{L_2}{C_2})$.

The foregoing considerations will possibly be better understood from the following explanation of Figs. 7, 8, and 9. Figs. 7 and 8 show a schematic diagram of the characteristics of the tuning elements, capacity and self-inductance, and their interaction. On the left-hand side of Fig. 7, a capacity characteristic is shown, having an initial value of a and a final value of b , over a horizontal scale deflection of x , where x may vary between zero and a maximum value c . The

intermediate values of the capacity are chosen so as to follow the law

$$y = a \left(\frac{b}{a} \right)^{\frac{x}{c}}$$

The elementary definition of a logarithm makes $\frac{x}{c}$ equal to the logarithm of $\frac{y}{a}$ from the above formula, wherein the logarithmic base is $\frac{b}{a}$. This base is to underlie all logarithms mentioned in this description.

The above formula

$$y = a \left(\frac{b}{a} \right)^{\frac{x}{c}}$$

may be written

$$\frac{x}{c} = \log y - \log a.$$

The difference of $\frac{x_2}{c} - \frac{x_1}{c}$ for two values of y_1 and y_2 is equal to

$$\begin{aligned} \frac{x_2 - x_1}{c} &= (\log y_2 - \log a) - (\log y_1 - \log a) \\ &= \log y_2 - \log y_1 = \log \frac{y_2}{y_1} \end{aligned}$$

from which it appears that the shift

$$\frac{x_2 - x_1}{c}$$

is equal for any two instrument values as long as their ratio $\frac{y_2}{y_1}$ is constant.

This explains the equation $y^2 = y_1 y_2$ given at the right-hand side of Fig. 7, where the inductance characteristic is shown as of the same nature as the capacity characteristic.

As stated above, the characteristic of the instrument was chosen in accordance with a mathematical function

$$y = a \left(\frac{b}{a} \right)^{\frac{x}{c}}$$

which makes the ratio $\frac{x}{c}$ the logarithm of the respective instrument values. Therefore a scale mounted on the moving instrument element will show a logarithmic characteristic, this being evident from the capacity scale shown on the lower edge of the moving element 27 of Fig. 7 which is read in reference to the fixed pointer shown thereunder.

There remains to be explained how the second scale, the wave length scale, (shown on the upper edge of element 27, Fig. 7) is correct for any setting of the capacity and self-inductance. The wave length of an electric oscillation is proportional to the

square root of the product of the capacity and self-inductance. The horizontal shift of the capacity is, by the above choice and elementary definition of a logarithm, proportional to the logarithm of the capacity value. The horizontal shift of the inductance is likewise proportional to the logarithm of the inductance value.

As shown in Fig. 8, the shift of the wave length scale in reference to its pointer is equal to the sum of the two individual shifts of the two elements, therefore proportional to the logarithm of the product of these two element values. In fact, the square of the wave length is proportional to the product of the inductance and capacity and the correctness of the indication of this scale for wave lengths is therefore apparent.

A brief explanation of the principles involved in the showing of Fig. 9 will now be given. When all of the capacity of an oscillatory circuit is located in the capacity instrument the simple logarithmic characteristic is given to this capacity instrument. When a fixed capacity, however, is in series with the instrument capacity, the instrument capacity has to be given such capacity values as will in conjunction with the fixed capacity give a resultant capacity of the circuit having the logarithmic characteristic.

Such is the case with an antenna circuit of a wireless receiving set. The antenna capacity is to be considered constant and in series with the instrument capacity. The resultant of the antenna capacity and the instrument capacity must in any position of the instrument capacity show a logarithmic characteristic.

In Fig. 9, C_1 denotes the required resultant capacity of true logarithmic characteristic. The antenna capacity C_s is shown as a horizontal line as it is constant and does not vary with different setting of the instrument.

The problem of the designer is therefore to find the characteristic of the instrument capacity, C' , in such way as to give in series with the fixed antenna capacity, C_s , the resultant desired logarithmically varying total capacity C_1 .

Two capacities C_s and C' in series give a resultant capacity equal to

$$55 \quad C_1 = \frac{1}{\frac{1}{C_s} + \frac{1}{C'}}$$

from which fundamental formula follows:

$$60 \quad C' = \frac{1}{\frac{1}{C_1} - \frac{1}{C_s}}$$

65 which yields the curve C' from the given curves C_1 and C_s .

As this calculation involves reciprocal values of capacities, the reciprocal curve $\frac{1}{C_1}$ has been drawn in the diagram of Fig. 9 for convenience in calculating the curve C' . The variable self-inductance is found in a similar but somewhat simpler manner as it is merely the difference between the logarithmic value which it is desired to obtain for the circuit and the value of the constant self-inductance of said circuit.

In Fig. 13 is shown diagrammatically the arrangement of the gearing for coupling together the inductance and the capacity elements and the wave meter in connection therewith. I and II illustrate the system of gearing for the receiving system illustrated in Fig. 4 or 5. In these views, (I, II of Fig. 13) the capacities and inductances are shown side by side for convenience of illustration instead of being arranged one on top of the other, the capacities being marked C' , C and the inductances L' , L . The arrows indicate the direction of rotation while the plus and minus signs illustrate the increase or decrease in the values. II indicates that the gears for the respective inductance and capacity elements are in mesh at the points marked z while I indicates that the said gears are in mesh with a central gear wheel at the points marked w . By the coupling arranged as indicated at II the capacity and inductance elements for the antenna circuit can be adjusted simultaneously, one increasing and the other decreasing, but independently of the corresponding elements for the oscillating circuit, while in I the coupling of the elements is such that all are operated simultaneously by turning any one of the elements or by turning the central gear wheel. In the arrangement last mentioned, the self-inductance and capacity may both be increased or decreased in both circuits simultaneously, whereby more rapid and greater changes in wave length are possible than where only one tuning element is varied in each circuit.

In III is indicated the coupling for a system such as is shown in Fig. 3, when the capacity and inductance elements are arranged side by side.

The wave meter scale is shown as attached to the central gear, at v .

What I claim is:

1. In a syntonizing apparatus for systems of wireless communication, inductances and capacities, and common means for simultaneously adjusting the same coincidentally and in a regular relation to each other over a working range of values.

2. Wireless apparatus comprising an antenna system and an associated oscillating system, said systems respectively containing inductance and capacity, and common means for simultaneously adjusting said inductance and capacity.

tances and capacities to vary the oscillation period while maintaining the system substantially in syntony.

3. Wireless apparatus comprising an antenna system and an associated oscillatory system, said systems respectively containing inductance and capacity, and common means for simultaneously adjusting said inductances and capacities, said inductances and capacities being also individually adjustable.

4. Wireless apparatus comprising the combination, with an antenna circuit including an antenna element of predetermined constant capacity and inductance value, and inductance and capacity in circuit with said antenna element, of an associated oscillating circuit having variable inductance and capacity and having capacity and inductance corresponding to said predetermined constant capacity and inductance value of said antenna element, and common means for simultaneously varying the variable inductances and capacities of said antenna and oscillating circuits.

5. Wireless apparatus comprising an antenna system having a variometer and a condenser arranged therein, an associated oscillating system having a variometer and a condenser therein, said variometers and condensers having individual operating members and means operable to couple said members together for simultaneous movement in regular relation.

6. Wireless apparatus comprising an antenna system having a variometer and a condenser arranged therein, an associated oscillating system having a variometer and a condenser therein, individual operating members for said variometers and condensers and gearing to couple said operating members for simultaneous movement in regular relation.

7. In a wireless system, the combination, with an antenna circuit and an oscillating circuit in inductive relation to said antenna circuit, each circuit having a part of its total inductance and capacity constant and another part variable, of common means for simultaneously varying the variable inductances and capacities of the two circuits while maintaining substantial syntony.

8. In a wireless system, the combination, with an antenna circuit and an oscillating circuit in inductive relation to said antenna circuit, each circuit having a part of its total inductance and capacity constant and another part variable, the fixed portions of the inductance and capacity of the antenna circuit having predetermined ratios to the corresponding fixed portions of the inductance and capacity of the antenna circuit, of common means for simultaneously varying the variable portions of the inductances and capacities of the two circuits while maintaining substantial syntony.

9. In a wireless system, the combination, with an oscillating circuit having capacity and self-inductance, of means for adjusting said capacity and self-inductance to vary the tune of the circuit, and common means for simultaneously varying said capacity and self-inductance while maintaining the circuit at a substantially constant tune.

10. In a wireless system the combination, with an oscillating circuit having capacity and self-inductance, of common means for simultaneously varying said capacity and self-inductance in such a manner as to maintain their product substantially constant.

11. In a wireless system, the combination, with an oscillating circuit, a variable capacity element and a variable inductance element included therein, and a detector circuit energized from said oscillating circuit, of common means for simultaneously varying the relative values of inductance and capacity while maintaining their product constant, whereby the condition for maximum audibility of the detector is positively determined.

12. In a wireless apparatus, the combination, with a variable condenser, a variable inductance device, and means for operating each independently, of a clutch device for locking the two operating means together, and releasable mechanism holding said clutch out of operation.

13. Wireless apparatus comprising, in combination, two associated oscillatory circuits, a variable tuning element in each circuit, and common means movable to vary the electrical values of said tuning elements, while maintaining substantial syntony, the variations in value of said tuning elements produced by a movement of said means bearing, respectively, substantially the same relation to said movement that y bears to x in the equation

$$y = a \left(\frac{b}{a} \right)^{\frac{x}{c}}$$

where a , b , and c are constants.

14. Syntonizing apparatus for wireless systems which comprises inductance and capacity, and common means operable to adjust the relative values of said inductance and capacity simultaneously and in such manner as to vary their ratio while maintaining their product constant.

15. Wireless apparatus comprising the combination, in an oscillatory system, of variable inductance and capacity, and common means operable to vary said inductance and capacity simultaneously without altering the electrical period of said system.

16. Wireless apparatus comprising the combination, in an oscillatory system, of a variable tuning element, and means movable to adjust said tuning element, the electrical

value of said tuning element varying with respect to the distance traversed by said movable means substantially as y varies with respect to x in the equation

5

$$y = a \left(\frac{b}{a} \right)^{\frac{x}{c}}$$

where a , b , and c are constants.

- 10 17. Wireless apparatus comprising the combination, in an oscillatory system, of variable inductance and capacity, means movable to adjust said inductance and said capacity individually to tune the system for 15 a definite wave length, the electrical values of said inductance and capacity varying with respect to the movement of said means substantially as y varies with respect to x in the equation

20

$$y = a \left(\frac{b}{a} \right)^{\frac{x}{c}}$$

where a , b , and c are constants, said inductance and capacity being further simultaneously variable to alter the stiffness of the system substantially without changing its tune.

- 25 18. Wireless apparatus comprising oscillatory circuits, variable tuning elements in 30 said circuits, means movable to vary the electrical values of said tuning elements individually to syntonize said circuits, and common means operable to vary the electrical values of said tuning elements simultaneously and thereby to change the electrical 35 period of said circuits without altering the ratio of stiffness between them and without destroying syntony.

- 40 19. Wireless apparatus comprising the combination, in an oscillatory circuit, of a variometer, a variable condenser, means movable to adjust said variometer and said condenser individually to tune the circuit, the movement of said means being related to the 45 resultant changes in said variometer and condenser as y is related to x in the equation

50

$$y = a \left(\frac{b}{a} \right)^{\frac{x}{c}}$$

where a , b , and c are constants, the variometer and the condenser being also simultaneously variable to vary the ratio of inductance to capacity without changing the tune 55 of the circuit.

- 20 20. Wireless apparatus comprising, in combination, inductance, capacity, controlling members movable to vary said inductance and capacity individually in accordance with an exponential function of the distance moved by said members, and means 60 operable to couple said controlling members for simultaneous movement, equal movements of the coupled controlling members 65 effecting equal percentage changes in said

inductance and capacity but in opposite senses.

21. Wireless apparatus comprising oscillatory circuits including tuning elements, sets of contacts respectively connected to tapping-off points on said tuning elements, contact members connected in the respective circuits and movable individually to engage contacts in said sets for independent tuning of said circuits, and common means operable to move a pair of said contact members simultaneously while maintaining substantial syntony.

- 70 22. Wireless apparatus comprising an antenna circuit including a tuning element, a closed oscillatory circuit operatively associated with said antenna circuit and including a tuning element, sets of contacts electrically connected, respectively, to tapping-off points on said tuning elements, switch members each individually movable with respect to a set of said contacts for independently syntonizing said circuits, and common means whereby said switch members may be moved to vary the electrical period of the circuits 75 simultaneously.

- 80 23. Wireless apparatus comprising oscillatory circuits including tuning elements, sets of suitable contacts respectively connected to tapping-off points on said tuning elements, a member individually movable with respect to each said set of contacts to vary the electrical value of the corresponding tuning elements independently of each other, and common means operable to move 85 a pair of said members simultaneously while maintaining substantial syntony.

- 90 24. A wireless system comprising oscillation circuits including tuning elements, sets of contacts electrically connected to said tuning elements and representing, respectively, different electrical values thereof, contact members respectively and individually movable to engage said sets of contacts and included in said circuits for independent 95 tuning thereof, and common means operable to move said contact members simultaneously to vary the electrical periods of said circuits according to a regular relation.

- 100 25. Wireless apparatus comprising oscillatory circuits including tuning elements, sets of contacts electrically connected to said tuning elements and representing, respectively, different electrical values thereof, contact members connected in the respective circuits 105 and individually movable to engage contacts in said sets for independent tuning of said circuits, and common means operable to move a pair of said contact members simultaneously while maintaining substantial syntony.

- 115 26. Wireless apparatus comprising oscillatory circuits including tuning elements, sets of suitable contacts electrically connected to said tuning elements and representing, 120

130

- respectively, different electrical values thereof, a member individually movable with respect to each set of contacts to place in circuit different values of the corresponding 5 tuning element for independent tuning of said circuits, and common means operable to move a pair of said members simultaneously while maintaining substantial syntony.
- 10 27. A wireless system comprising oscillation circuits including tuning elements, contacts electrically connected to one of said tuning elements and representing different electrical values thereof, a contact member 15 individually movable with respect to said contacts to place in circuit different values of said tuning element, a member individually movable to vary the electrical value of another of said tuning elements, and common means operable to move both said members simultaneously to vary the electrical periods of said circuits according to a regular relation.
- 20 28. The combination with an antenna, of an inductive winding, capacity associated therewith for determining wave length or frequency, switching mechanism for bringing into circuit more or less of said winding without changing the capacity, and 25 means co-operating with and mechanically connected with said switching mechanism for changing said capacity after predetermined variation of said winding.
- 25 29. A circuit arrangement comprising two associated oscillatory systems arranged for successive transfer of signals therethrough, said systems respectively containing inductance and capacity and common means for simultaneously adjusting said inductances 30 and capacities to vary the oscillation period 40 while maintaining the system substantially in syntony.
- 30 30. A circuit arrangement comprising two associated oscillatory systems, said systems 45 respectively containing inductance and capacity, means for adjusting said inductances and capacities individually and common means for simultaneously adjusting said inductances and capacities.
- 35 31. High frequency signaling systems comprising in combination, two associated oscillatory circuits, a variable tuning capacity in each circuit and common means movable to vary the electrical values of said 50 capacities while maintaining substantial syntony, the variation of said capacity produced by a movement of said means bearing, respectively, substantially the same relation to said movement that y bears to x 55 in the equation

$$y = a \left(\frac{b}{a} \right)^{\frac{x}{c}},$$

60 where a , b and c are constants.

32. High frequency signaling systems comprising in combination two associated oscillatory circuits, a variable tuning element in each circuit and common means movable to vary the electrical values of said tuning elements while maintaining substantial syntony, the variations in value of said tuning elements produced by the movement of said means being so related that a given movement progressively increases the rate 70 of change in the value of said tuning elements.

33. High frequency signaling systems comprising in combination two associated oscillatory circuits, a variable capacity in 80 each circuit and common means movable to vary the electrical values of said capacities while maintaining substantial syntony, the variations in values of said capacities produced by a movement of said means being so 85 related that a given movement progressively increases the rate of change in the value of said capacities.

34. High frequency signaling systems comprising in combination, two associated oscillatory circuits, a variable tuning element in each circuit and common means movable to vary the electrical values of said tuning elements while maintaining substantial syntony between said circuits, each of said 90 elements being so dimensioned that the corresponding values of the tuning elements and the displacements of said means vary 95 substantially according to the equation

$$y = a \left(\frac{b}{a} \right)^{\frac{x}{c}},$$

100 where y is the value of the electrical element, x the displacement and a , b and c are 105 constants.

35. High frequency signaling systems comprising in combination, two associated oscillatory circuits, a variable tuning capacity in each circuit and common means movable to vary the electrical values of said 110 capacities while maintaining substantial syntony between said circuits, each of said capacities being so dimensioned that the corresponding values of the capacities and the 115 displacements of said means vary substantially according to the equation

$$y = a \left(\frac{b}{a} \right)^{\frac{x}{c}},$$

120 where y is the capacity, x the displacement and a , b and c are constants.

36. In high frequency signaling systems the combination of two associated oscillatory 125 circuits arranged for successive transfer of signals therethru, separate inductances and capacities for determining the tuning of said circuits and means for simultaneously and substantially correspondingly increasing 130

ing or decreasing the tuning frequency of said circuits for obtaining selectivity comprising a single common adjusting member arranged to simultaneously increase or decrease the value of said capacities, the variations in values of said capacities produced by a movement of said member being so related that a given movement progressively increases the rate of change in the value of said capacities.

37. In high frequency signaling systems the combination of two associated oscillatory circuits arranged for successive transfer of signals therethru, separate inductances

and capacities for determining the tuning of 15 said circuits and means for simultaneously and substantially correspondingly increasing or decreasing the tuning frequency of said circuits for obtaining selectivity comprising a single common adjusting member 20 arranged to simultaneously increase or decrease the value of said capacities, said capacities being of substantially equal values and having substantially like electrical characteristics throughout their range.
